Attorney

UNITED STATES PATENT OFFICE.

VIRGIL M. HADDON, OF OMAHA, NEBRASKA.

DUMPING-TRUCK.

1,359,363.

Specification of Letters Patent. Patented Nov. 16, 1920.

Application filed March 23, 1920. Serial No. 368,088.

To all whom it may concern:

Be it known that I, VIRGIL M. HADDON, a citizen of the United States, residing at Omaha, in the county of Douglas and State 5 of Nebraska, have invented certain new and useful Improvements in Dumping-Trucks, of which the following is a specification.

This invention relates to an improvement in dumping trucks, and has for its principal 10 object to provide convenient means for a control of the swinging movements of the box and end gate, the parts to be few and simple for these purposes so that they will be durable and may be economically manufactured.

The invention consists of the novel construction, combination and arrangement of parts as described herein and claimed, and as illustrated in the accompanying drawing 20 wherein—

Figure 1 is a side view showing the rear end of the dumping truck. Fig. 2 is a view of the same showing the position of parts when dumped. Fig. 3 is a view showing the 25 side of the truck opposite to the side shown in Fig. 1. Fig. 4 is a view of the rear end of the truck, the scale being reduced.

The invention is illustrated and described in connection with a truck 5 which may be 30 of ordinary construction. At 6 is indicated a box-frame, rectangular in side elevation, the side-plates *a* for the base of said frame being pivotally mounted as indicated at 7, adjacent to their rear ends upon the truck 35 frame 8, near the rear end thereof. Numerals 9 indicate cross-bars which are secured to the upright parts of the box-frame for supporting the inclined bottom 10 of the box, said bottom having any desired degree 40 of inclination found to be of advantage, the side-plates and front end-plate of the box being respectively indicated at 11 and 12.

Pivotal mounted, as indicated at 13, at the top of the box, at its rear open end is 45 the end-gate 14. The downward, rearward inclination of the bottom 10 is such that, while the pivotal mounting 7 from which the box may swing, is somewhat nearer to its rear than its front end, the load will be 50 practically balanced, since, when in a nor-

mal position, the volume of that part of the box rearwardly of the pivotal mounting 7 will be approximately equal to the volume of the remaining part of the box, which facilitates a control of the swinging movements thereof. 55

For this control I provide a hand lever 15 normally disposed in a horizontal position at the side of a driver's seat 16, its rear end being pivotally mounted upon a bracket 17 which is secured to the truck frame, a link 18 being provided which has a pivotal mounting 19 for its upper end upon the front end of the box-frame, midway between the top and bottom thereof, the lower end of 60 said link being connected with the hand lever between the ends thereof by means of a pivot 20, and it will be understood that an upward swinging movement of the hand lever will cause a swinging movement of 65 the box to the position shown in Fig. 2 of the drawing. 70

Numeral 21 indicates a locking-bar operating to prevent any upward swinging movement of the front end of the box and preventing dumping of a load while driving over obstructions or while moving upwardly upon inclines, the lower end of said bar being pivotally mounted upon the hand lever 15, near the outer end of the latter, as indicated at 22 and its upper end engaging loosely in a staple 23 which is mounted upon the side of the box-frame, said bar being provided with a lug or ledge 24 adjacent to its upper end; and it will be understood that 75 when the box is disposed in a normal position the ledge 24 will engage the staple to prevent any upward swinging movement of the hand lever. Numeral 25 indicates a hand-piece or releasing-member for the locking-bar, which is pivotally mounted forwardly of said bar upon the hand lever 15, and it will be understood that a driver of 80 the truck, by swinging the front end of the hand-piece downwardly, will cause its rear end to engage the lug *x* of the locking-bar, below its pivotal mounting 22, which will cause disengagement of its ledge 24 with the staple 23, and the driver may then 85 swing the lever 15 upwardly, the link 18 90 95 100

causing the front end of the box to swing upwardly, as described, for dumping the load.

In order that the end gate 14 will have an outward swinging movement while the box is moving as last mentioned, and that said gate may be moved to a closed position when the lever 15 is swung downwardly, I provide a pull-and-push rod 26, its front end being mounted upon the pivot 20 of lever 15 and its rear end having a pivotal connection 27 with the end gate. It will thus be seen that the movements of the end gate to open and closed positions require no attention of a driver, and that the degree of speed for the swinging movement of the box for the purpose of dumping will depend upon the swinging movement of the end gate, the result being that, during the operation of dumping, the load will move gradually from the box, and excessive jolting or shocks usually caused by a sudden release of the load will be avoided. Also a driver, by use of the lever 15, may control the movements of the box and end gate to permit a gradual or more rapid discharge of the load while the truck is moving, this being of advantage when spreading of the load is required.

In order that the end gate may be uniformly pressed against the end of the box, a second pull-and-push rod, indicated at 26' (Fig. 3.), is disposed at the side of the box opposite to the rod 26, its front end being pivotally mounted upon a pivot 20' of a rock lever 15' which is mounted pivotally at its lower end upon a bracket 17', the rear end of said rod 26' being pivotally mounted upon the end gate as indicated 27', a link 18' being connected with the pivot 20' and with the front end of the box-frame, the parts 26' and 18' being similar in proportion to the parts 26 and 18 above mentioned; and in operation, when the lever 15 is swung forwardly to move the box-frame to a horizontal position, the rod 26' will swing forwardly with considerable force, simultaneously with the forward movement of the rod 26 for closing the end gate, and on account of its effective weight will maintain the "off" end of the gate with which it is connected in contact with the rear end of the box, this being an important feature in operation since the truck may be used as a carrier for material which is plastic, and by use of the construction described, a forward movement of the hand lever 15 will cause a corresponding movement of the rods 26 and 26' for pressing the end gate against the rear end of the box, the links 18 and 18' which will then be disposed inclinedly, operating to maintain said pressure of the end gate until the lever 15 has been swung upwardly.

Numerals 28 indicate stop-lugs provided for the sides of the box-frame, near the lower part of its front end, said lugs projecting outwardly of the sides of said box-frame, their function being to prevent the link 18 from being disposed in line with the hand lever 15, and to prevent the link 18' from being disposed in line with the rock-lever 15', this being of advantage since it facilitates a forward swinging movement of the hand lever when moving the box frame to a horizontal position after the load has been dumped.

What I claim as new and desire to secure by Letters Patent is,—

1. In combination with a vehicle frame, a box open at its rear end and having an inclined bottom and pivotally mounted between its ends upon the vehicle frame, a gate having its upper end disposed between and pivotally connected with the sides of the box, a hand-lever mounted upon and normally projecting forwardly of the vehicle frame, a link having its lower end pivotally mounted upon and between the ends of the hand-lever, its upper end being mounted upon the front end of the box between the top and bottom thereof, a pull-and-push rod having its front end pivotally connected with the hand lever its rear end being connected with the end gate, said hand-lever being adapted to have an upward swinging movement to move the pull-and-push rod rearwardly for coincidentally opening the gate causing a swinging movement of the vehicle box.

2. In combination with a vehicle frame, a box pivotally mounted between its ends upon the vehicle frame, said box having a bottom inclined from its front to its rear end, an end gate having its top disposed between and pivotally connected with the sides of the box, a hand lever mounted on the vehicle frame, a link having its respective ends mounted on the box and said hand lever, a pull-and-push rod connecting the hand lever with the end gate, and a locking-bar adapted to removably engage the box and pivotally connected with the hand lever outwardly of the mounting, on said hand lever, of the link and said pull-and-push rod.

3. In combination with a vehicle frame, a box having an inclined bottom and pivotally mounted between its ends upon the vehicle frame, an end gate having its top disposed between and pivotally connected with the sides of the box, a hand lever mounted upon the vehicle frame, a pivot-pin carried by the hand lever, a link mounted on the pivot-pin of the hand lever and pivotally connected with the box, a pull-and-push rod mounted on the pivot-pin of the hand lever and pivotally connected with the

gate, and a locking-bar pivotally mounted on the hand lever adjacent to said pivot-pin for engaging said box.

4. In combination with a vehicle frame 5 a box having an inclined bottom and pivotally mounted between its ends upon said frame, a gate having its top disposed between and pivotally connected with the sides at the rear end of the box, a pair of levers 10 pivotally connected with the sides of the vehicle frame and normally extending forwardly of said box, a pair of links each being pivotally connected with the box and

with a lever, a pair of pull-and-push rods each being connected with the gate and a 15 lever, one of said levers being movable in a circle's arc to cause simultaneous swinging movements of said links and rods for causing simultaneous swinging movements of the box and gate. 20

In testimony whereof, I have affixed my signature in presence of two witnesses.

VIRGIL M. HADDON.
